UNITED STATES PATENT OFFICE.

ELLWOOD M. SHANNON, OF BALA, PENNSYLVANIA.

MALLET LOCOMOTIVE.

Application filed September 9, 1926. Serial No. 134,445.

The object of my invention is to so construct a "Mallet" locomotive that the exhaust pipe leading from the rear cylinder of the structure to the exhaust nozzle in the smoke-box of the boiler will avoid the mechanism below the boiler. This object I attain by extending the exhaust pipe or pipes through the waist bearer of the locomotive as fully described hereinafter.

10 Reference may be had to the accompanying drawings in which:

Fig. 1 is a side view, partly in dotted lines, of the front end of a "Mallet" locomotive, illustrating my invention;

15 Fig. 2 is a sectional view on the line 2—2, showing a single exhaust pipe;

Fig. 3 is a detached perspective view of the waist bearer; and

20 Fig. 4 is a sectional view showing two exhaust pipes.

1 is a portion of the rear frame of the locomotive, and 2 is the forward frame. These two frames are connected by a pivot 3. 4 is a boiler having a smoke-box 5, and

25 this boiler is rigidly supported on the rear frame and overhangs the forward frame so that the forward frame can move laterally on the pivot 3, independently of the boiler. The frames and boiler are shown by dotted lines. 6 is the rear cylinder structure which is mounted on the rear frame 1, and 7 is the forward cylinder structure which is mounted on the outer end of the frame 2. The foregoing description refers to the ordinary type 30 of "Mallet" locomotive.

In order to support the overhanging portion of the boiler, a waist bearer 8 is secured to the boiler as shown, and rests on the transverse support 9 secured to the forward frame

40 2. On the waist bearer are ribs 10, over which extend hook-shaped brackets 11 secured to a transverse support 9. This is an ordinary type of waist bearer used on the "Mallet" locomotive.

45 The exhaust nozzle 12 is located in the smoke-box 5 of the boiler, and the exhaust pipe 13 leads from the forward cylinder 7 to the exhaust nozzle. The exhaust pipe is made telescopic as shown, and has a connection at each end so that it will accommodate itself to the movements of the boiler and the forward frame.

An exhaust pipe 14 leading from the rear cylinder 6 to the exhaust nozzle 12 is rigidly mounted, as it does not move independently of the rear frame of the boiler. The pipe

14 in the present instance is made in three sections, 14^a, 14^b and 14^c. The section 14^a leads from the exhaust passage at one side of the cylinder structure 6, and is connected 60 to the section 14^b by a joint 15. At this point the pipe 14 is supported by a bracket 16 depending from the boiler 2. The pipe 14^b extends through an opening 17 in the waist bearer 8, as clearly shown in Fig. 2. 65

The pipe is preferably flattened in cross-section, where it extends through the opening 17 in the waist bearer, and the flattened portion preferably extends to the point where the section 14^b is coupled to the section 14^c, the coupling extending through the shell of the smoke-box of the boiler so as to provide a support for the section 14^b as well as for the section 14^c. By extending the pipe 14 through the waist bearer and flattening 75 it at the point shown, the pipe can be arranged close to the boiler and free of any mechanism that is located between the boiler and the forward frame. The section 14^c of the pipe 14 is connected to an extension 19 80 at one side of the nozzle 12.

In some instances, two longitudinal exhaust pipes 14^d—14^d may extend from the rear cylinder to a point near the nozzle 12^a, where the pipes are connected to a bifurcated 85 section 18 which is coupled to an extension of the nozzle. In such case, one pipe extends through an opening 17^a in one side of the waist bearer and the other pipe extends through the opening 17^a in the opposite side 90 as shown in Fig. 4.

I claim:—

1. The combination in a "Mallet" locomotive, of a rear frame; a forward frame pivotally connected to the rear frame; a boiler mounted on the rear frame and extending over the forward frame; a cylinder structure mounted on each frame; a waist bearer on the boiler; a support for said bearer mounted on the forward frame, the waist bearer having an opening therein; and an exhaust pipe leading from the rear cylinder structure through the opening and connected to the nozzle in the smoke-box of the boiler. 100

2. The combination in a "Mallet" locomotive, of a rear frame; a forward frame pivotally connected to the rear frame; a boiler mounted on the rear frame and extending over the forward frame; a cylinder structure mounted on each frame; a waist bearer 105 on the boiler; a support for said bearer mounted on the forward frame; an opening 110

in the waist bearer on each side of the centre thereof; and an exhaust pipe leading from the rear cylinder structure through one of the openings and connected to the nozzle in the smoke-box of the boiler.

3. The combination in a "Mallet" locomotive, of a rear frame; a forward frame pivotally connected to the rear frame; a boiler mounted on the rear frame and extending over the forward frame; a cylinder

structure mounted on each frame; a nozzle in the smoke-box of the boiler; an exhaust pipe leading from the forward cylinder structure to the nozzle; a pipe leading from the rear cylinder structure to the nozzle; and a waist bearer having an opening therein for the passage of the pipe, the pipe being flattened at the point where it extends through the waist bearer. ¹⁵
